UNITED STATES PATENT OFFICE.

JOHN G. SAUER, OF NEW YORK, N. Y., ASSIGNOR TO HIMSELF, AND
WILLIAM J. WETTER, OF MEMPHIS, TENNESSEE.

NUMBERING-HEAD FOR PRINTING-PRESSES.

SPECIFICATION forming part of Letters Patent No. 374,708, dated December 13, 1887.

Application filed November 4, 1886. Serial No. 217,981. (No model.)

To all whom it may concern:

Be it known that I, JOHN G. SAUER, of the city, county, and State of New York, have invented a new and Improved Numbering-Head for Printing-PresSES, of which the following is a full, clear, and exact description.

My invention relates to a numbering-head for printing-presSES constructed with a main casing and inner frame carrying the numbering-disks, and arranged to receive an out-and-in movement in the main casing from contact with the platen of the press, which movement is utilized to turn the numbering-disks for consecutively numbering the sheets as they are printed.

The invention consists of the construction, arrangement, and combination of parts, all as hereinafter described and claimed.

Reference is to be had to the accompanying drawings, forming a part of this specification, in which similar letters of reference indicate corresponding parts in all the figures.

Figure 1 is a perspective view of a part of a printing-press, showing my new numbering-head set up with the type. Fig. 2 is a plan view of the numbering-head with one of the side plates removed, parts being shown in section to show the construction. Fig. 3 is a sectional elevation taken on the line $x-x$ of Fig. 2. Fig. 4 is a perspective view of the inner frame removed from the main casing. Fig. 5 is a perspective view of the front pawl-yoke for turning the numbering-disks. Fig. 6 is a perspective view of the numbering-disks removed from the inner frame. Fig. 7 is a transverse sectional elevation on the line $y-y$ of Fig. 2; and Fig. 8 is an end view of the inner frame, showing the ratchet-wheel and pawl in the position they are held by the end piece of the main outer frame, no part of the latter being shown except the pivots of the ratchet and pawl shown in section. Fig. 9 is an enlarged elevation of the numbering-head, the back plate being broken away to clearly show the click k and pin l .

A represents the main casing, composed of the end pieces, a a' , back plate, a'' , (which unites the said two end pieces.) and the two removable side plates, b b' . The casing A is adapted to be set up with the type in the printing-press, as illustrated in Fig. 1, and it receives

the inner frame, B, which carries the numbering-disks d d' , back pawls, e e' , and pawl-yoke C, provided with the front pawl-plate, f , pivoted in the yoke and held forward by the spring f'' , 55 and provided, also, with several pawls f' , for turning the numbering-disks d successively, as hereinafter described.

The inner frame, B, which carries the disks d and pawl-yoke C upon the shaft g , on which 50 they turn easily, is placed in the main casing A, and is normally held, forced somewhat out therefrom by the action of the two springs h , so that when pressure comes upon the disks d in printing the inner frame will be forced into 65 the main casing a short distance against the pressure of the springs h . This inward movement is utilized for turning the yoke C forward upon the shaft g for causing the pawls f' , acting in conjunction with the ratchets g' , 70 formed upon the side of the numbering-disks, to turn said disks to bring the typed surfaces thereof successively into position for printing. The movement of the pawl-yoke C is effected through the medium of the lever j , pivoted to 75 the outside of the inner frame, B, and provided with a stud, j' , that reaches through a slot, j'' , and enters the slot j''' , made in one of the check-pieces f'' of the yoke C, so that the swinging of the lever j will communicate a 80 like motion of the yoke C and the pawls f carried thereby. The yoke C and lever j are normally pressed to the position shown in Figs. 7 and 8 by the action of the lightspring i pressing upon the edge of one of the check-pieces of the yoke. The yoke and lever j will occupy this position at the time the platen 85 of the press strikes the disks d in printing, and the contact of the platen with the disks d will prevent them from turning upon the shaft g , 90 and at this time the platen will press the whole inner frame, B, within the outer main frame, A. This inward movement ceases when the outer surfaces of the disks d reach "type-high" position, and during this movement 95 the lever j strikes the stud e' , formed upon the small ratchet-wheel e , and turns said wheel against the tension of the coiled spring e'' , which is set in a recess, e'' , formed in the inner surface of the end piece, a' , of the main 100 frame A. The ratchet-wheel e is set in said recess e'' over the spring e' , and said wheel is

made fast to a short shaft, e^4 , journaled in the end piece, a' , and the inner end of the spring e^2 is attached to this shaft, while its outer end is made fast to the inner surface of the recess 5 e^3 , so that the turning of the ratchet-wheel e , by the inward movement of the lever j , as above stated, puts a tension upon the said spring e^2 , and this tension is retained by the check h , attached to the inner surface of the 10 end piece, a' , of the main casing A. The inner corner of the inner frame, B, is provided with a pin, l , which reaches over the tail-piece of the click k , as shown in Fig. 8, so that when the platen of the printing-press is moved out 15 of contact with the disks d , and the frame B thus left free to be moved outward by the springs h , the said pin will trip the click k , thus leaving the ratchet-wheel e free to be turned in the direction of the arrow in Fig. 8, which 20 will cause stud e' to move lever j downward or outward, which in turn will swing the yoke C outward and cause the pawls f' thereof to turn the disks d one space, ready for the next impression. This action is repeated with each 25 reciprocation of the inner frame, B.

To prevent the disks d from being turned too far and from turning back, I provide the inner frame, B, with the above-mentioned back pawls, e , pivoted upon the rod e' , which 30 pawls are pressed against the ratchets g' , as shown in Fig. 7, by the plate-springs c^2 , one for each pawl. These pawls e , pressing, as they do, against the long angle of the ratchet-teeth of the wheels, also serve to stop the disks d 35 in their revolution exactly in the proper position, so that the type thereof will squarely strike the paper and produce a good impression.

The series of pawls f' are of gradually-diminishing length, as shown in Fig. 5, and in each of the ratchet-wheels g' is formed a notch, g^2 , into which the point of the pawls drop after a complete revolution of the disks, so that at the outset the longest pawl f' will

turn the end disk (the others remaining at 45 rest) until the said longest pawl reaches the recess g^2 . The point of the pawl will then drop into this recess and thus bring the next shorter pawl into action, which will continue until the recess in its ratchet-wheel is reached, 50 whereupon the next pawl in like manner will come into action, and so on through the whole set of pawls.

Having thus fully described my invention, what I claim as new, and desire to secure by 55 Letters Patent, is—

1. The main casing A, provided at one end with a spring, e^2 , and ratchet e , having pin e' , in combination with the click k , attached to the main casing, the inner casing, B, the lever j , 60 and the pin l , for tripping the click, substantially as described.

2. The main casing A, provided at one end with a spring, e^2 , and ratchet e , having pin e' , in combination with the reciprocating inner 65 casing or frame, B, provided with the numbering-disks, the pawl-yoke C, the click k , and lever j , substantially as and for the purposes set forth.

3. The main casing A, provided with the 70 coiled spring e^2 , ratchet-wheel e , pin e' , and click k , in combination with the inner casing, B, provided with the lever j , and pawl-yoke C, all arranged to operate substantially as and for the purposes described.

4. The inner frame, B, provided with the numbering-disks d , pawl-yoke C, and lever j , for operating the numbering-disks, and placed in the main frame provided with springs h , in combination with a studded ratchet-wheel located in the main casing and acted upon by a spring and check, the inner frame being provided with a pin, l , for tripping the check, substantially as and for the purposes set forth.

JOHN G. SAUER.
